(57) **ABSTRACT**

The present invention provides a pull bar and method for using the pull bar. The pull bar is used to pull together flooring boards that utilize a click-and-lock system. A handle is rigidly connected at an angle to a tapping block. A puller is rigidly connected to the underside of the tapping block. The puller has an angled lip that extends downward from the tapping block. A hook is connected to the angled lip and is for hooking a flooring board.

FIG. 12

FIG. 13

1

PULL BAR FOR CLICK-AND-LOCK
FLOORING SYSTEMS

The present invention relates to click-and-lock flooring systems, and in particular, to pull bars for click and lock flooring systems.

BACKGROUND OF THE INVENTION

Engineered wood flooring and laminate flooring are known in the prior art. Engineered flooring is made of high-quality plywood with a veneer of pre-finished fine hardwood on top. Laminate flooring is made of thin, pressed wood board with an image of wood on top covered by a clear wear layer to protect the image.

Engineered flooring and laminate flooring are typically installed by using a click-and-lock system. There are several different click-and-lock systems available, but all use a design that can best be described as a modified tongue-and-groove. Instead of a straight tongue fitting directly into the groove on an adjoining plank, the pieces must be angled and tapped so that a shaped tongue fits into a matching groove in the adjoining piece. The planks fit together in a tight lock that can only be separated if the boards are angled back in the reverse direction. This flooring layer typically "floats" on the underlayment, with no adhesives or gluing necessary. Click-and-lock flooring may also be used for luxury vinyl tiles and planks.

FIGS. 1-4 show the prior art method for installing a click and lock engineered flooring 20. In FIG. 1, an installer is installing engineered flooring 20 utilizing a prior art click-and-lock system. FIG. 2 shows a close up, perspective view of engineered flooring boards 10a and 10b. Tongue 11 is being inserted into groove 12.

FIG. 3 shows a side view of tongue 11 and groove 12. Tongue side 15 and groove side 16 include further locking features 25 and 26, respectively, that function to hold the boards together once the boards have clicked into place (FIG. 4). To properly connect planks 10, the installer has angled board 10b and he is pulling it towards board 10a. It is necessary to angle board 10 so that tongue 11 inserts into groove 12 at the easiest, most efficient angle. The installer will pull the planks together as tight as he can with his hands, as shown in FIG. 1. Often the installer will find it necessary to tap board 10b with a hammer with sufficient force so that board 10b will click into board 10a and lock into position, as shown in FIG. 4.

Pull bars are known and are sometimes used during the installation process. The utilization of prior art pull bars can lead to damage of boards as the pull bar is pulled or tapped against the edge of the engineered flooring. For example, FIG. 4b shows prior art pull bar 93 positioned on top of board 10b. Hammer 94 impacting pull bar 93 can cause damage to lower edge 96 of groove side 16. Lower edge 96 takes the full force of the hammer's impact.

The prior art method shown in FIGS. 1-4b is currently used by most installers. Although effective to a skilled installer, it is nevertheless problematic. Over time, an installer can develop sore knees, sore hands and back problems. Also, valuable time may be wasted dealing with difficult alignment and installation problems. Furthermore, boards are sometimes damaged while trying to force a difficult click-and-lock insertion.

What is needed is a better pull bar for more efficient installation of click-and-lock flooring.

SUMMARY OF THE INVENTION

The present invention provides a pull bar and method for using the pull bar. The pull bar is used to pull together

2

flooring boards that utilize a click-and-lock system. A handle is rigidly connected at an angle to a tapping block. A puller is rigidly connected to the underside of the tapping block. The puller has an angled lip that extends downward from the tapping block. A hook is connected to the angled lip and is for hooking a flooring board.

BRIEF DESCRIPTION OF THE DRAWINGS

FIGS. 1-4b show prior art methods and devices for installing click-and-lock tongue and groove flooring.

FIGS. 5 and 6 show perspective views of a preferred embodiment of the present invention.

FIG. 7 shows a side view of a preferred embodiment of the present invention.

FIGS. 8-13 shows a preferred method for using a preferred embodiment of the present invention.

FIG. 14 shows another preferred embodiment of the present invention.

FIG. 15 shows another preferred embodiment of the present invention.

DETAILED DESCRIPTION OF THE
PREFERRED EMBODIMENTS

FIG. 5 shows a perspective view of a preferred embodiment of pull bar 30. Handle 1 is rigidly attached to block 2. Block 2 is rigidly attached to puller 3. Preferably handle 1 includes rubber grip 4. In a preferred embodiment handle 1, block 2 and puller 3 are fabricated from a metal or a metal alloy. Handle 1 is preferably welded to block 2 and puller 3 is preferable riveted to the bottom of block 2 via rivets 18 (FIG. 6). In a preferred embodiment pull bar 30 is approximately 14 inches long.

FIG. 7 shows a side view of pull bar 30. Puller 3 is approximately 5 inches long and includes angled lip 37 having lower hook 38. Angled lip 37 is not perpendicular to but is rather angled away from block 2 as shown. Lower hook 38 hooks back towards block 2 as shown. Handle 1 is rigidly connected to block 2 at an angle connection that is preferably equal to approximately a 20-degree angle from horizontal.

UTILIZATION OF THE PRESENT INVENTION

FIGS. 8-13 illustrate a preferred method of using pull bar 30.

In FIG. 8, the installer has laid down engineered flooring board 10a on the floor. Spacer 50 separates board 10a from the wall. Board 10b has been placed next to board 10a in a position soon to be installed.

In FIG. 9 the installer has set pull bar 30 on top of board 10b. Angled lip 37 is angled outward away from block 2 so as to be able to reach lower edge 96 of board 10b. The upper portion of angled lip 37 contacts upper edge 103 of board 10b so that a hammer impact against tapping block 2 will have its force absorbed by both lower edge 96 and upper edge 103. This will reduce the possibility of damage to board 10b or to lower edge 96. Hook 38 extends underneath lower edge 96 as shown.

In FIG. 10, the installer has grabbed handle 1 of pull bar 30. The installer has pulled board 10b towards board 10a at only a very slight angle. The installer is stopped from pulling board 10b closer due to the modified tongue and groove junction between boards 10a and 10b. To properly lock board 10b to 10a, the installer will need to tilt board 10b to a greater angle.

In FIG. 11, the installer has pressed down on handle 1. This has caused board 10b to tilt counterclockwise so that there is an increased angle between tongue 11 and groove 12. The angle will make it easier to lock board 10b into board 10a via the click-and-lock system described above. After positioning board 10b at the appropriate angle, the installer is tapping on block 2 with hammer 94 to easily move tongue 11 into groove 12.

In FIG. 12 the installer has successfully locked board 10b to board 10a.

In FIG. 13 the installer has removed pull bar 30 from board 10b. Now further boards may be installed in a similar fashion.

OTHER PREFERRED EMBODIMENT

FIG. 14 shows another preferred embodiment of the present invention. In FIG. 14, shock absorption piece 99 has been placed between angled lip 37 and board 10b. Shock absorption piece 99 will absorb shock forces when hammer 94 strikes block 2. In one preferred embodiment shock absorption piece 99 is hard foam. It may also be fabricated from rubber, silicone or plastic.

FIG. 15 shows another preferred shock absorption piece 101. Shock absorption piece 101 has been formed to very closely match the curvature of groove side 16 of board 10b. This will provide even better shock absorption protection of groove side 16 so that a strike on tapping block 2 would be absorbed by shock absorption piece 101, minimizing the risk of damage to upper groove edge and said lower groove edge

Although the above-preferred embodiments have been described with specificity, persons skilled in this art will recognize that many changes to the specific embodiments disclosed above could be made without departing from the spirit of the invention. For example, although the above description stated that block 2 was rigidly connected to puller 3 via rivets, it could also be rigidly connected using other methods. For example block 2 can be welded to puller 3. Therefore, the attached claims and their legal equivalents should determine the scope of the invention.

What is claimed is:

1. A pull bar for pulling together flooring boards utilizing a click-and-lock connection system, said pull bar comprising:

- A. a tapping block,
- B. a handle rigidly connected at an angle to said tapping block, and
- C. a puller rigidly connected to said tapping block, said puller comprising:
  - i. a lip extending downward from said tapping block wherein said lip is an angled lip that extends downward and is angled away from said tapping block, and
  - ii. a hook connected to said lip, said hook for hooking one of said flooring boards

wherein each of said flooring boards comprises a groove side having a lower groove edge and an upper groove edge, wherein said angled lip contacts said upper groove edge and said lower groove edge so that a strike on said tapping block would be absorbed by both said upper groove edge and said lower groove edge.

2. The pull bar as in claim 1, wherein said puller is riveted to said tapping block.

3. The pull bar as in claim 1, wherein each of said flooring boards comprises a lower groove edge, wherein said hook extends under said lower groove edge.

4. The pull bar as in claim 1 wherein said angle of said handle is approximately 20 degrees.

5. The pull bar as in claim 1 wherein said angle of said handle is at least 10 degrees.

6. The pull bar as in claim 1 further comprising a shock absorption device attached to said lip and said hook.

7. A method for using a pull bar for pulling together a first flooring board and a second flooring board utilizing a click-and-lock connection system, each flooring board comprising a tongue side and a groove side, said method comprising the steps of:

A. placing said tongue side of said first flooring board next to said groove side of said second flooring board,

B. setting a pull bar on top of said first flooring board, said pull bar comprising:

- i. a tapping block,
- ii. a handle rigidly connected at an angle to said tapping block, and

iii. a puller rigidly connected to said tapping block, said puller comprising:

- a. a lip extending downward from said tapping block, and

b. a hook connected to said lip, said hook for hooking a lower groove edge of said first flooring board,

C. pushing downwards on said handle to raise said first flooring board to an insertion angle,

D. tapping said tapping block with a blunt instrument to lock said first flooring board to said second flooring board,

E. locking said first flooring board to said second flooring board, and

F. removing said pull bar from said first flooring board.

8. The method as in claim 7, wherein said puller is riveted to said tapping block.

9. The method as in claim 8, wherein said lip is an angled lip that extends downward and is angled away from said tapping block.

10. The method as in claim 9, wherein each of said flooring boards comprises a groove side having a lower groove edge and an upper groove edge, wherein said angled lip contacts said upper groove edge and said lower groove edge so that a strike on said tapping block would be absorbed by both said upper groove edge and said lower groove edge.

11. The method as in claim 8, wherein each of said flooring boards comprises a lower groove edge, wherein said hook extends under said lower groove edge.

12. The method as in claim 8 wherein said angle of said handle is approximately 20 degrees.

13. The method as in claim 8 wherein said angle of said handle is at least 10 degrees.

14. The method as in claim 8 further comprising a shock absorption device attached to said lip and said hook.
